UNITED STATES PATENT OFFICE.

WILLIAM A. WALES, OF NEWTON, ASSIGNOR TO AUBURNDALE WATCH COMPANY, OF WESTON, MASSACHUSETTS.

REVERSIBLE SCREW-DRIVER.

SPECIFICATION forming part of Letters Patent No. 236,738, dated January 18, 1881.

Application filed September 30, 1880. (No model.)

To all whom it may concern:

Be it known that I, WILLIAM A. WALES, a citizen of the United States, residing at Newton, in the county of Middlesex and State of 5 Massachusetts, have invented a new and useful Improvement in Reversible Screw-Drivers, which improvement is fully set forth in the following specification and accompanying drawings, in which—

10 Figure 1 represents a view, in perspective, of my invention. Fig. 2 is a sectional elevation. Fig. 3 is a cross-section, and Fig. 4 views showing the invention as adapted to other tools.

15 This invention relates to certain improvements in that class of reversible tools having a tool proper pivoted in a bifurcated handle, so that either end of the tool may be turned to position for use; and it has for its object to 20 provide an improved means for holding the tool in position, as more fully hereinafter specified.

In the drawings, A is the bifurcated handle, holding between its jaws the blade of tools B, 25 which is pivoted, at or near its middle, into the lower ends of the jaws a. The blade B is held rigidly in position by means of a sleeve or collar, C, that slides on the lower part of the handle, and which is prevented from coming entirely off by the projecting ends of the 30 pivot b, which acts as a stop or rest for the sleeve.

When it becomes necessary to reverse or 35 turn the blade around, the collar is slid up toward the top of the handle past the slit, thus allowing the blade or tool to be changed; then

the sleeve is slid back into position to hold the tool ready for use.

The pivot may be made removable, so that one handle can be used for a variety of blades 40 or tools, if desired.

It is obvious that the device can be used for a large number of tools of different kinds where it is desirable to have two sizes of the same implement in constant use and at convenient command, or two implements in the same handle, such as a screw-driver and gimlet combined, when it is necessary to use one tool 45 after the other.

I am aware that a reversible tool pivoted to 50 a handle having a sliding spring-clamp to grasp one end of the tool and hold it in position has been heretofore used, and such I do not claim.

Having thus described my invention, what 55 I claim as new, and desire to secure by Letters Patent, is—

As a new article of manufacture, a reversible tool consisting of a cylindrical shank provided with a suitable handle and bifurcated at its 60 lower end, a reversible blade pivoted between the lower ends of the members, and an annular slide adapted to work on said shank and confine the blade at or near its point of attachment, the said slide being held in position by 65 means of the rivet by which the blade is secured, substantially as specified.

WILLIAM ATHERTON WALES.
